ORGAN

Sylvan K. Ketterman, Muncie, Ind.

Application November 26, 1948, Serial No. 61,984

12 Claims. (Cl. 84—351)

1

This invention relates to organs, and more particularly to air operated organs utilizing reeds as sound producing elements.

One of the objects of my invention is to provide a generally improved reed organ which can be produced for sale at a reasonable cost.

As another object, my invention comprehends the provision of a small wind operated organ having good tone quality and which operates to produce sufficient volume for a wide variety of uses without the use of amplifiers or other such electronic equipment.

My invention has for another object the provision of a small wind operated organ embodying a power driven blower as a part of a unitary organ structure, and having parts so constructed and related that the operation of the blower and the movements of air to and from the tone producing parts are at all times quite silent.

The organ of this invention embodies a quantity, variety and arrangement of keys, reeds and stops such that a sufficient scale coverage in a variety of tonal effects, as well as a two-manual organ effect are obtainable.

It is further within the purview of my invention to provide an organ wherein sound producing elements of the free reed type are disposed in a cell structure and in a sound chamber or chest in order to produce a mellow resonant effect, such as that attained from the pipes of a large organ; the chamber or chest, for volume control purposes being equipped with a variable control panel actuated by a foot controlled swell pedal.

In this organ, the keys actuate valves, as is usual, but I have so constructed and arranged the keys and their respective valves that each key acts quite directly to effect movement of its respective valve, and each valve is so disposed with respect to the direction of air flow that the normal pressure tends to seat the valve and offers limited resistance to the initial lifting of each valve from its seat, whereby sharp valve opening and closing movements are effected, so as to produce crisply defined notes and a desirable key "touch" response.

The valve arrangement and structure of my organ is also related to the sound producing reed ensemble in a manner such that a single valve controls air flow through a plurality of reeds of a given pitch and different tone characteristics, and the reed tone characteristics used at any one time are selective operations of stop keys.

I have brought within the purview of this invention the provision of electromagnetically actuated stop valves embodied in the air flow sys-

2

tem of the organ in a manner such that both gravity and normal air pressure tend to move the stop valves to their normally closed positions.

As a further object, my invention comprehends the provision of a system of valves and traps in the air flow system for regulating the air flow to an amount dependent upon the playing demands and such that the flow is silenced when the demand is low.

10 Accessibility to reeds for replacement, cleaning or adjustment is provided in the preferred structure of my reed organ by providing supports for those reeds from which they are removable by slipping them from a retaining slot and by providing valves carried and biased in such a way that they are readily moved from and to operating and out-of-the-way positions and biased to those positions when moved thereto.

Other objects and advantages of the invention 20 will be apparent from the following description and the accompanying drawings in which similar characters of reference indicate similar parts throughout the several views.

Referring to the four sheets of drawings; 25 Fig. 1 is a perspective view taken from the front and somewhat to one side of one form of a unitary organ structure embodying a preferred form of this invention;

Fig. 2 is a fragmentary top plan view of a portion of the organ structure shown in Fig. 1 and depicting a preferred arrangement of the playing and stop keys utilized in the preferred form of my organ;

Fig. 3 is a rear sectional view of the organ 30 shown in Fig. 1 wherein certain parts are cut-away to illustrate details of interior construction and arrangement;

Fig. 4 is a fragmentary side sectional view taken substantially on a line 4—4 of Fig. 3 and drawn to a larger scale than Fig. 3;

Fig. 5 is a diagrammatic top plan view illustrating the arrangement of valves and air passages utilized in the disclosed organ structure;

Fig. 6 is a front elevational view of a preferred 45 type of reed structure adapted to use in the organ of my invention;

Fig. 7 is a fragmentary top plan view which depicts a preferred type of valve structure and arrangement adapted to use in this organ, and

50 Fig. 8 is a perspective view of a control mechanism utilized in the disclosed organ structure.

Having reference to the accompanying drawings, the exemplary embodiment of my invention which is disclosed for illustrative purposes comprises a unitary and semi-portable organ struc-

ture which is preferably contained, in its entirety, in a case 10 or housing, along the front of which a key bed 12 supports a set of keys 13 arranged in the manner of those of a piano and utilized for the manual selection of notes in playing the instrument. As is usual in organs, in addition to the selection of notes by the keys 13, there are additional available selections of the tone characteristics or combinations of tone characteristics, as well as certain effects which, in the present instance, are chosen by the manual movements of stop keys 14 disposed above and to the rear of the keys 13 and movably carried so as to project from a stop panel 15 which forms a part of the case 10. Facing forwardly of the organ 10 and above the keyboard is a music rest 16 secured to a top panel 17 of the case and projecting upwardly in angular relationship thereto.

It is my preference that the case 10 of the disclosed organ shall not only carry all of the operating parts of the organ so that it is unitary and self-contained but also that the case shall form a practically complete enclosure for those operating parts. In the present instance, the case includes end panels 18 and 19, a lower front panel 20 below the key bed and a removable back panel 22 in addition to the aforementioned top panel 17, key bed 12, stop panel 15 and key mechanism cover panels 23 and 24.

In my preferred structure, the interior of the case 10 is divided into compartments which, in the present instance, comprise a secondary resonant chamber 25 extending substantially all of the way across the upper portion of the case interior, a blower compartment 26 below one end of the secondary resonant chamber and a compartment 27 occupying the other end of the portion of the space below the secondary resonant chamber, which latter compartment serves as a housing for additional operating parts of the organ mechanism. A movable cover 28 secured to the top panel 17 by a hinge 29 serves as a tone louver and normally closes an opening 30 in the mid-portion of the top panel; said tone louver being adapted to close the top of the case when the organ is not in use and to serve as an output volume control, depending on whether it is open or closed while the organ is being played.

The bottom of the secondary resonant chamber is defined by a partition 32 which extends the full width of the interior of the case from the end panel 18 to the end panel 19. A partition 33 extends vertically from the bottom wall 34 of the case to the mid-portion of the partition 32 and separates the blower compartment 26 from the compartment 27.

As one precaution against the dissemination of undesirable mechanical noise from the blower, which would be particularly noticeable when the organ is being played softly or during silent periods, the entire interior of the blower compartment 26 is preferably lined with sound insulating material 35 of substantial thickness, which material may be one of the relatively soft fibrous materials utilized for that purpose. As a further precaution against the production of undesirable noise, either mechanically produced by the vibration of the blower or resulting from air flow, a box 36 is mounted within the bottom portion of the blower compartment 26 and serves as an enclosure for an electric blower motor 37 which carries a blower fan 38. The interior of the box 36 is lined with sound insulating material 39. Adjacent the mid-portion of the fan an air

inlet opening 40 is provided in an end wall 42 of the blower box 36. An air outlet opening 43 is provided in the top of the box and communicates with the interior of the blower compartment 26. To provide an outlet for air from the blower compartment 26, an air passage 44 is provided in the partition 33 and the insulating material adjacent that partition.

At the air inlet opening 40 of the blower box 36, the flow of air produced by the blower is proportioned to the playing demands of the organ and silenced by a bellows structure 45 which covers the inlet opening 40 and has, in addition to a flexible bellows wall 46, an end wall 47 spaced from the end wall 42 of the blower box and hingedly supported along to the upper edge for swinging movement toward and from the inlet opening 40. A compression spring 48 normally biases the bellows end wall 47 away from the end wall 42 of the blower box and is preferably mounted interiorly of the bellows with one end bearing against the end wall 42 of the blower box and its other end braced against a cap 49 which is removably secured to the bellows end wall 47, so that the spring is accessible for replacement and cleaning. A cover 50 is carried on the interior of the bellows structure by a post 52 secured to the bellows end wall 47 and is aligned, as well as of a size, to cover the inlet opening 40 when moved toward that opening against the biasing forces of the spring 48. This cover has a plane surface facing the inlet opening which, by preference, is covered with a layer 53 of material such as felt. Above the blower box 36, the interior of the bellows structure 45 has an air flow connection to a flexible conduit 54 which, in turn, has an end connected to an opening 55 in the partition 33.

With the bellows structure thus constructed for the control of air flow into the blower box through the inlet opening 40, the reduced pressure within the blower box 36 which is effected when there is little or no flow of air into the bellows structure through the conduit 54 causes the bellows to collapse to a position such that the cover 50 covers the air inlet opening 40. On the other hand, when the flow of air to the interior of the structure through the conduit 54 is increased, the effect is to increase the air pressure within the bellows structure, so as to allow that bellows structure to expand as a result of the biasing force of the spring 48 whereupon the cover 50 moves away from the inlet opening 40 in an amount proportioned to the air flow.

For effecting further silencing of the mechanical noise of the blower and the air flow, it is my preference to provide a trap door 56 made of a light material, such as wood, and hingedly secured to the top of the blower box 36 at a position to cover the outlet opening 43. This trap door carries a sealing surface pad 57 and is normally biased to a closed position with respect to the outlet opening 43 by gravity; the trap door being sufficiently light in weight that air pressure forces the trap door from the opening when there is a substantial flow of air through that opening. Within the compartment 27, the air passage 44 is provided with a similar gravity controlled trap door 58 which carries a sealing pad 59 and is hingedly supported along one edge at a position normally to cover the outlet end of the air passage 44.

Within the secondary resonant chamber 25, front and rear walls 60 and 62 respectively (Fig. 4) and end walls, such as 63, (Fig. 3) extend up-

wardly from the partition 32 and support a cell block 64 above the partition 32, so that those walls and the cell block, together with the partition 32 define an air chamber 65 extending almost the entire width of the organ case below the cell block and communicating with the blower through the flexible conduit 54 and bellows structure 45. Above the cell block 64, the front and rear walls 60 and 62 and end walls such as 66, together with a movable cover 67 define a primary resonant chamber or swell chamber 68; the cover 67 being secured to the top of the rear wall 62 by hinges 69 so that it is swingable upwardly from a normally closed position to serve as a swell for controlling the volume output of the organ. In my preferred structure which is disclosed, the weight of the cover 67 is counter-balanced to a large extent by resilient means which, in this instance, is in the form of a resilient metal rod 70 having end portions 72 and 73 disposed in substantially right angular relationship to the relatively long mid-portion of the rod and projecting into bores in the edges of the cover and rear wall, as shown in Figs. 3 and 4. The normal angular dispositions of the end portions 72 and 73 are such that when the cover is in the closed position, the mid-portion of the rod 70 is twisted.

Having reference to Figs. 1, 3 and 8, the swell provided by the cover 67 is adapted to be actuated to a position providing the desired volume output by a swell pedal 74 movably mounted for foot control in an opening 75 in the lower front panel 28 of the organ case. As depicted in Figs. 3 and 8, the swell pedal 74 is hingedly mounted for swinging movement in a vertical plane by a hinge block 76 secured to the bottom wall of the case and having a hinge pin 77 extending through a block 78 secured to the inner pedal surface. A stop 79 is desirably provided for limiting the inward movement of the swell pedal. Near its movable end, remote from the hinge block 76, a link 80 movably connects the swell pedal to an arm 82 of a crank 83, which crank comprises a rod portion 84 carried for rotation by bearing blocks 85 secured to the bottom wall 34 and having the arm 82 secured to one end and another arm 86 secured to the other end. The normal angular positions of the crank arms 82 and 86 are such that swinging movement of the arm 82 downwardly toward a horizontal position in response to similar pedal movement effects corresponding upward swinging movement of the arm 86 from a substantially horizontal position. The upward swinging movement of the end of the arm 86 effects upward movement of a link 87 which is connected thereto. At its upper end, the link 87 has a slot 88 in which a projecting pin 89 on the edge of the cover is disposed. The pin 89 being displaced from the axis of the cover hinges 69, the cover is moved upwardly by movements of the link 87 and returns by gravity upon release of the force exerted through the latter link.

As depicted in Fig. 6, the reeds utilized to produce tones or audible notes of various frequencies in this exemplary embodiment of my invention each includes a metal yoke 90 having elongated and substantially parallel side portions 92 and 93 with an elongated opening 94 therebetween in which a vibratory reed 95 is resiliently supported at one end. The passage of air through the opening 94 and adjacent the reed effects vibratory movement of the reed at a frequency dependent upon characteristics, such as the mass and resilience thereof. The characteristics of the reed structure, in addition to controlling its fun-

damental vibrating frequency, also control the tone characteristics or harmonic vibrations which it produces. In use the reeds are each supported by a supporting structure through the yoke, while the vibratory reed portions are free to move upon the flow of air relative thereto.

In my preferred reed organ structure, the cell block 64 provides a firm and solid foundational structure for supporting the reeds; the cell block 10 being constructed and arranged and having sufficient mass in itself to provide a solid base from which the pure reed tones emanate, without that cell block structure having extraneous vibrations set up therein or in any way interfering with the emanation of those pure reed tones. As depicted in the diagrammatic view of Fig. 5, the disclosed cell block carries five sets of reeds, each of which sets includes reeds having predetermined fundamental frequencies and covering a preselected 20 frequency range; the sets being arranged in rows designated as P, M, V, D and B and each of the sets having different tone characteristics. It may be readily understood that various numbers of such sets and various tone qualities for the sets 25 may be provided. In the present instance, the sets are characterized by the terms "Bourdon," "Diapason," "Viola," "Melodia" and "Principal." The respective equivalent organ pipe lengths are 16 feet, 8 feet, 8 feet, 8 feet and 4 feet. In each 30 of the sets there are the same number of reeds or notes similarly arranged and having the reeds of each fundamental frequency aligned laterally of the rows.

In effecting the foregoing arrangement, as well 35 as rigidity, in the cell block structure, my preferred form of cell block is constructed of longitudinally extending block sections 96, 97, 98, 99 and 100, each of which has therein a series of uniformly spaced reed cavities, such as 102, 103, 40 104, 105 and 106, as depicted in Figs. 4 and 7. In each instance, the reed cavities open downwardly of the block sections at the top and along the front sides of the respective block sections. Also, as depicted in Figs. 4 and 7, reed retaining 45 grooves 107, 108, 109, 110 and 112 are provided adjacent the front openings of the reed cavities and extend along both sides of one end of the respective reed cavities from the open ends thereof, so that the reeds such as 90P, 90M, 90V, 50 90D and 90B, are movably carried in their respective reed cavities by being pushed into the reed retaining grooves from the open upper ends of the reed cavities. Thus, in each instance, the vibratory tongues of the reeds are exposed to the 55 interior of the reed cavities and to the front openings of the block sections and are effectively interposed between the front and top openings of the block sections.

Intermediate the adjacent and substantially 60 parallel block sections 96, 97, 98, 99 and 100, longitudinally extending marginal strips 113 are secured to the respective block sections in spaced and substantially parallel relationship to define air flow channels 114, 115, 116, and 117 in communication with the reed cavities of the block 65 sections 97, 98, 99 and 100 respectively. This construction unites the block sections into a relatively solid cell block of laminated construction and including air passages for the flow of air to the reeds of the series, as well as the individual reed cells. On the opposed front and rear surfaces of the block thus formed, additional marginal strips 118 and 119 are secured to the block sections in separated and substantially parallel relationship. These strips not only serve

as supports for the cell block when secured to the front and rear walls 60 and 62 of the air chamber 65 but the strips 118 define a channel 120 communicating with the reed cells of the front block sections 96. As depicted in Fig. 3, the ends of the air flow channels 114, 115, 116, 117 and 120 are closed by lateral strips such as 122 at the opposite ends of the cell block.

Although the reeds of each row provide a continuous sequential series of notes from one end of the cell block to the other, it is my preference in the present structure to partition the air flow channels 114, 115, 116, 117 and 120 at aligned positions near the mid-portion of the series, as depicted by dotted lines at 123 in Figs. 3 and 5. This partitioning together with the provision of air flow valve controls for selectively opening and closing the passage of air to the separate portions of the divided air flow channels serves in the production of a two-manual organ effect. The disclosed organ, as indicated in Fig. 5, has 61 notes ranging from C to C. The partitioning of the reed series to provide upper and lower stops is at the mid-portion of the range between E and F, so that there are 32 notes in the upper stop and 29 notes in the lower stop.

As indicated in Fig. 5, the air flow channels 120, 114, 115, 116 and 117 in the lower stop section communicate with the air chamber 65 through openings 124, 125, 126, 127 and 128 which openings are preferably disposed in longitudinally and laterally staggered relationship relative to one another. Likewise, the air flow channels 120, 114, 115, 116 and 117 of the upper stop group communicate with the air chamber 65 through openings 129, 130, 132, 133 and 134 respectively. The openings of the latter group are also preferably disposed in longitudinally and laterally staggered relationship in the lower surface of the cell block. Over each of the respective openings 124, 125, 126, 127, 128, 129, 130, 131, 132, 133 and 134 on the lower surface of the cell block, I have provided a valve box 135, 136, 137, 138, 139, 140, 142, 143, 144 and 145. As depicted in Figs. 3 and 4, each valve box has in its lower surface two air flow passages 146. Each such air flow passage 146 is normally closed by a valve 147; the valves in each instance being biased to the closed position by both gravity and a light spring 148 (Fig. 4). As shown in Fig. 4, each valve 147 is carried for independent opening and closing movements by a magnetic armature 149 actuated by an electromagnet 150. It may be noted that with the arrangement disclosed, the valves 147 open against the normal force of the air pressure effected by the blower, in addition to being biased to the closed position by gravity and their respective springs 148. Thus, failure to operate leaves the valve closed. Also, the operation against the air pressure effects quick opening movement. Furthermore, the use of two valves in parallel relationship in each valve box, either of which valves controls an opening of sufficient size to permit air flow for satisfactory operation, provides a safety factor against the failure of stop valve operation.

As depicted in Fig. 4, each of the stop keys 14 extends through an opening 152 in the stop panel 15 and is supported for swinging movement in a vertical plane relative to a pivot shaft 153; the stop key being notched to receive the shaft and held in position against the shaft by a curved leaf spring 154. One end of the curved leaf spring 154 is supported by an anchor screw 155 which is carried by the stop panel 15, while

the other end of the leaf spring engages a notch in the surface of the stop key opposed to the pivot shaft 153. The effective action line of each spring 154 is such that it crosses the axis of the pivot shaft 153 during movements from one of its operating positions to the other, whereby the stop keys are biased to the position to which they are manually actuated; one position being determined by a stop pad 156 on one surface of the opening 152, and the other position being determined by a stop pad 157 on the opposed opening surface.

Each stop key has an inwardly extending end portion 158 aligned for effecting actuation of normally separated and resilient switch contacts 159 and 160 carried by insulating support strips 162. A transformer 163 and a rectifier 164 mounted on the bottom wall 34 of the case in the compartment 27 (Fig. 3) are adapted to be connected to a suitable alternating current power source and to provide direct current for the actuation of the stop valve electromagnets 150. In each instance, the circuit to the stop valves in one of the valve boxes is controlled by the contacts actuated by one of the stop keys, that for convenience in producing a full organ effect, a contact bar 165 is actuated by a "full organ" stop key 166 to engage a series of contacts 167, thereby closing the circuits to all of the stop valve electromagnets by the operation of a single stop key.

With the disclosed arrangement of stop keys, air passages and valves, the respective valves in the boxes 135, 136, 137, 138 and 139 which control the flow of air through openings 128, 127, 126, 125 and 124 to the air flow channels of the cell block to the reeds in the lower register are actuated by movements of the stop keys 14B, 14D, 14V, 14M and 14P. Likewise, the valves for the upper register of notes which are enclosed in boxes 145, 146, 143, 142 and 140 are controlled by actuation of the stop keys 14B', 14D', 14V', 14M' and 14P' respectively. Through the selections effective by manual actuation of various ones and combinations of the stop keys, different selections of tone characteristics and combinations thereof may be made in both the upper and lower register of notes.

As has been previously explained, the reeds are arranged in rows in the cell block and the reeds of those rows are aligned laterally of the rows. Also, the individual reed cells in the cell block open into the primary resonant chamber 63. Air flow to the reeds of the rows is selectively controlled in both the upper and lower registers of notes by valves 141 actuated by movements of the stop keys 14. In addition, the selection of notes for playing the organ by manual movements of the keys 13 is effected through an additional set of valves 168 actuated by movements of those keys.

The valves 168 are substantially alike in structure, each is actuated by an individual key and each valve is of a size and normally disposed to cover and close the open ends of an aligned group of reed cells transverse to the rows of such cells and having the same fundamental tone frequency. As shown in Figs. 4 and 7, each such valve comprises a strip of wood or other light material 169 carrying, on its cell covering surface, a layer 170 of a relatively soft sealing material, such as leather which normally covers the cell openings of one group. Each of the strips has a longitudinal groove 172 in its upper surface and is carried for movement from and toward its nor-

mally closed position over one group of cell openings by a crank-type actuating element 173.

Each crank-type element has aligned bearing portions 174 and 175 journaled for rotational movement in bearing strips 176 and 177 disposed in spaced relationship to opposite sides of the cell block. Intermediate the bearing portions 174 and 175, each crank-type actuating element has a straight mid-portion 178 displaced to one side of the axis of the bearing portions and substantially parallel thereto, which straight portion is of a length to fit into the longitudinal groove 172 of a valve strip, the fit being sufficiently snug to carry the valve strip while allowing preliminary rotational movement of the strip to a seating position over a group of reed cells. At the front ends, the actuating elements have projecting crank portions 179 which, in the present instance, are disposed in coplanar relationship with the offset mid-portions of the actuating elements, so that a force exerted upwardly on the projecting end of the crank portion of any actuating element effects an individual and upward opening movement of the valve carried thereby.

Springs 180 are utilized normally to bias the actuating elements and their respective valves to the closed position. Each such spring has an end connected to the projecting crank portion 179 of the actuating element, while its other end is anchored to a stationary pin 182 disposed below the crank portion. In my preferred structure, and as depicted in Fig. 7, the projecting crank portions 179 of the actuating elements include portions 183 having obtuse angular relationship to the bearing axis and the crank end portion and which not only serve as the crank arms of the crank portions, but also provide slides for the ends of the biasing springs 180. Also, the anchored ends are so positioned with respect to the crank portions that in addition to normally biasing the actuating elements and their respective valves to the closed position, the springs slide along the portions 183 when a valve is moved to an out-of-the-way position as illustrated at the right hand side of Fig. 7. In the latter position, the spring does not interfere with the valve movement to an out-of-the-way position and serves to hold it in that latter position when manually moved thereto. With any valve in such an out-of-the-way position, it may be observed that the group of reeds controlled by that valve is accessible for removal by sliding movement endwise and outwardly of the reed retaining grooves. In addition to the normal biasing forces of the respective springs 180 to hold their valves in the closed position, it is noteworthy that each such valve is actuated against the normal force of the operating air pressure in moving from its seated position over the reed cells. This provides for a quick opening action and has a tendency to keep the seating surfaces free of dust.

As shown in Fig. 4, each key 13 is supported for rocking movement relative to a balance rail 184 by balance rail pads 185 and balance rail pins 186, which latter pins extend through substantially V-shaped slots in the key. Downward movement of the exposed ends of the keys during the playing of the instrument is limited by pads 187 on pins 188 and carried by a front rail 189. Intermediate the balance rail 184 and the front rail 189, a key leveling screw rail support 190 extends upwardly from the key bed 12 and carries a key leveling screw rail 192, which rail, in turn, carries key leveling screws

193 for each of the keys. At the rear or inner ends, the keys of the disclosed structure are each cut longitudinally so as to provide an adjustable take-up tongue 194 underlying the projecting end of the crank portion 179 of one of the valve actuating elements. The pad 195 is interposed between the take-up tongue 194 and the projecting end of the crank portion and a take-up screw 196 is threaded into the take-up tongue to effect an adjustment such that the valve for each key is closed when the key is in a normal level position.

With the disclosed key structure, downward pressure applied to the exposed or playing end of a key raises the inner or rear end of the key lever and correspondingly lifts the projecting end of the crank portion of a valve actuating element so as to raise and thus open one of the valves 172 against the biasing force of its spring and the air pressure to expose an aligned group of reeds for air flow thereto. Any one or more of such exposed reeds to which there is also communication for the flow of air through the stop valves 147 will be caused to vibrate for producing a tone as the result of the air flow. With the key structures and valves mechanisms provided, it may be noted that the valves are free for movement to the out-of-the-way position shown in Fig. 7 without the necessity of releasing any mechanical connection between the valve actuating elements and their respective keys.

For the production of an additional effect adapted to use in playing the disclosed organ, a tremulant is provided. In my disclosed structure, this tremulant comprises a light weight shaft 197 of rectangular section extending across the front portion of the secondary resonant chamber 25 and supported for rotation at its ends by bearing blocks 198 and end shafts 199. On opposed faces, the shaft 197 has vanes 200 of a light, relatively thin and stiff material secured thereto and projecting oppositely and equidistantly therefrom along substantially the entire length of the shaft 197. At one end of the shaft 197, a drive pulley 202 is drivingly connected to the shaft and driven through a flexible driving element such as a belt 203 from a motor 204 secured to the end panel 19 of the case. The motor preferably has a uniform speed of rotation. In the present instance, and by way of example, the motor speed and drive pulley ratio are such that the speed of rotation of the shaft 197 and vanes 200 is approximately 200 revolutions per minute. When in operation, the tremulant gives a periodic fluttering effect to the sound output of the organ. A switch, which may be of the type utilized and described in connection with the stop keys for actuating the stop valves may be utilized for controlling the operation of the motor 204, and is operated by a stop key 205 (Figs. 1 and 2).

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A reed type wind operated organ comprising, in combination, a unitary cabinet structure, including a console carrying a set of keys mount-

ed in substantially coplanar relationship, a primary resonant chamber, a secondary resonant chamber, an air chamber and a compartment for operating parts, a cell block interposed between the air chamber and primary resonant chamber and including reed cavities and a channel providing communication for air flow between the air chamber and reed cavities, a series of reeds having different fundamental vibrating frequencies, there being a reed with a predetermined frequency for each of said keys and one of the reeds in each reed cavity, valves supported in a common plane parallel to the plane of the keys at the ends of the keys for individual movement and each carried by a rotary crank-type support providing an actuating connection to one of said keys, said valves each normally covering one end of a reed cavity in the cell block and controlling the flow of air through one of said reed cavities and the reed therein, a power driven blower mounted in said compartment and having an air flow connection to the air chamber, a cover hingedly mounted on the primary resonant chamber and serving as a swell, and a manually operable movable member exposed to the exterior of the cabinet structure and having a connection to said cover for effecting movements thereof to determine the volume output of the organ.

2. A reed type wind operated organ as defined in claim 1 and further characterized by a tremulant mounted in the secondary resonant chamber above the cell block and adjacent the top of the primary resonant chamber and including a shaft element mounted for rotation and extending longitudinally of the chamber, said shaft having blades secured thereto and projecting therefrom in opposed directions, and power actuated means for rotating the shaft at a preselected speed.

3. A reed type wind operated organ comprising, in combination, a unitary cabinet structure including a console carrying a set of keys, each of said keys having an adjustable end portion, a primary resonant chamber, a secondary resonant chamber, an air chamber and a compartment for operating parts, a cell block interposed between the air chamber and primary resonant chamber and including rows of reed cavities and channels providing communication for air flow between the air chamber and each row of reed cavities, a series of reeds in the reed cavities in each row and having different fundamental vibrating frequencies, there being a reed with a predetermined fundamental frequency for each of said keys in each of the rows and the reeds having the same fundamental frequency in the different rows being aligned laterally of the rows, valves supported for individual movement and each carried by a crank-type support movable relative to the cell block and providing an actuating connection to one of said keys, said valves each controlling the flow of air through one of said reed cavities of each row and the reeds therein, each of said crank-type supports having an end portion engaging the adjustable end portion of one of the keys, a power driven blower mounted in said compartment and having an air flow connection to the air chamber, and a manually operable movable member exposed to the exterior of the cabinet structure and having a connection to means for effecting variations in the volume output of the organ.

4. A reed type wind operated organ as defined in claim 3 and further characterized by parti-

tions in the mid-portions of said channels dividing each of the channels into portions through which air flow communication is provided between the air chamber and a part of the reed cavities of each row, and means for selectively opening and closing air flow communication between the air chamber and each of the channel portions.

5. A reed type wind operated organ as defined in claim 3 and wherein said blower is enclosed in a housing having air inlet and outlet openings, and each of said openings being provided with a closure element normally biased to close the opening, and the biasing forces on each of the closure elements being such that air pressure effects opening movements thereof when one or more of said valves is opened.

6. A reed type wind operated organ as defined in claim 3 and wherein said cell block comprises a unitary structure made up of wood blocks having the reed cavities therein and reed holding grooves adjacent the reed cavities, said reed cavities being open on the side adjacent the reed channels and at one end, said reed holding grooves opening into the reed cavities and being open at the open ends of the reed cavities so that the reeds are slidably into and from the ends of the reed holding grooves, and strips secured to and between said wood blocks to define said channels communicating with the open sides of the reed cavities.

7. In a reed type wind operated organ, the combination comprising a plurality of sets of reeds wherein the reeds of each set have different predetermined fundamental frequencies covering a range of musical notes, the reeds of the sets having the same fundamental frequencies and different tone characteristics, and the reeds having like fundamental frequencies being disposed

40 in adjacent relationship, a valve for controlling the flow of air to each of the sets of reeds, unitary key actuated valves for simultaneously starting and stopping the flow of air to adjacent reeds having the same fundamental frequencies, and 45 each of said key actuated valves including members movably supported by crank-type elements and having closed, open and out-of-the-way positions, said crank-type elements each having axially aligned bearing portions at opposite ends of 50 the valve member and being shaped to provide a valve carrying portion displaced laterally thereof to one side of the bearing axis and a crank portion displaced to the same side of the bearing axis.

55 8. In a reed type wind operated organ, the combination comprising a reed structure of the type adapted to the production of a musical note upon the flow of air therethrough, means including a key actuated valve having an element starting and stopping the flow of air through the reed structure, said valve element being carried for movements between closed, open and out-of-the-way positions by a crank-type member having axially aligned bearings at opposite ends of the 60 valve element, and a spring having one end connected to a portion of the crank-type element for normally biasing the valve element to the closed position, said portion of the crank-type element and said spring being so angularly disposed relative to one another that said one end of the spring moves along said portion during movement of the valve element between the open and out-of-the-way positions so as to bias the valve element to the out-of-the-way position when it is moved thereto.

9. In a reed type wind operated organ, the combination comprising a plurality of reeds, a cell block providing a relatively massive and solid support for the reeds, walls defining an air chamber on one side of the cell block and a resonant chamber on the opposite side of the cell block, said cell block having openings therein for the flow of air therethrough and relative to the reeds between the air chamber and resonant chamber, a second resonant chamber encompassing the first mentioned resonant chamber, and a movable partitioning element between the resonant chambers and providing a swell.

10. In a reed type wind operated organ, the combination comprising series of reeds, means defining an air flow passage to each series of reeds, and valve means for selectively opening and closing each air flow passage, said valve means including two similar valve openings for each air flow passage and an individually movable valve element biased to a closing position relative to each valve opening, and separate operating parts for moving the valve elements away from the valve openings.

11. In a reed type wind operated organ, the combination comprising a power driven blower, a sound insulated enclosure for said blower having air inlet and outlet openings therein, an expandible bellows mounted on the exterior of the enclosure over the air inlet opening and carrying a cover for movement toward and from a closing

position relative to the air inlet opening, resilient means biasing the bellows and cover away from the air inlet opening with a force of a magnitude to be overcome by a reduction of air pressure within the bellows effected by the blower and in an inverse relation to the volume of air flow to the blower, and a trap normally biased to close the air outlet opening, the biasing force on the trap being of a magnitude such that it is opened by flow of air from the blower.

12. In a reed type wind operated organ, the combination comprising a secondary resonant chamber, a primary resonant chamber within the secondary resonant chamber and having a movable cover for varying the opening for passage of sound from the primary resonant chamber to the secondary resonant chamber, a swell pedal, and a series of levers and links connecting the swell pedal and movable cover.

SYLVAN K. KETTERMAN.
